US00D329639S

United States Patent [19]

Arvanitakis et al.

[11] Patent Number: Des. 329,639

[45] Date of Patent: ** Sep. 22, 1992

[54] OPTOELECTRONIC ASSEMBLY

[75] Inventors: Nicolaos C. Arvanitakis, Vestal, N.Y.; Vincent J. Black, Austin, Tex.; Richard G. Nolan, Binghamton, N.Y.

[73] Assignee: International Business Machines Corporation, Armonk, N.Y.

[**] Term: 14 Years

[21] Appl. No.: 499,832

[22] Filed: Mar. 26, 1990

[52] U.S. Cl. D13/165; D13/133; D13/179

[58] Field of Search D13/133, 146, 147, 152, D13/179; 250/227.24, 551; 385/53, 58, 59, 90, 88, 92, 94; 361/394, 395

[57] CLAIM

The ornamental design for an optoelectronic assembly, as shown and described.

DESCRIPTION

FIG. 1 is a perspective view of an optoelectronic assembly, illustrating our new design;

FIG. 2 is a front elevational view thereof, on a reduced scale;

FIG. 3 is a rear elevational view thereof, on a reduced scale;

FIG. 4 is a side elevational view thereof, on a reduced scale, the opposite side being a mirror image;

FIG. 5 is a top plan view thereof, on a reduced scale; and,

FIG. 6 is a bottom plan view thereof, on a reduced scale.

The terminal pins shown in FIGS. 2, 3, 4 and 6 are illustrated in dashed form for environmental purposes only.

FIG. 2

FIG. 3

FIG. 4

FIG. 5

FIG. 6
